UNITED STATES PATENT OFFICE.

NAHUM FRANKLIN BRYANT, OF EAST BOSTON, MASSACHUSETTS.

IMPROVEMENT IN RAILWAY-CARRIAGES.

Specification forming part of Letters Patent No. 40,813, dated December 8, 1863.

To all whom it may concern:

Be it known that I, NAHUM FRANKLIN BRYANT, a resident of East Boston, in the county of Suffolk and State of Massachusetts, have invented certain new and useful Improvements having reference to Railway-Carriages; and I do hereby declare the same to be fully described in the following specification, and represented in the accompanying drawings, of which—

Figure 1 denotes a side elevation, Fig. 2 a vertical and longitudinal section, and Fig. 3 a vertical and transverse section, of my invention, this latter section being taken through the chock, to be hereinafter described. Fig. 4 is a horizontal section of such invention. Fig. 5 is a side view, and Fig. 6 an edge view, of the chock. Fig. 7 is a top view of the removable chock-stopper, which answers as a bottom for the chock-chamber of the housing.

My present invention has reference and is auxiliary to that for which Letters Patent No. 39,545 were granted to me on the 18th day of August, A. D. 1863, the design or purpose of the invention so patented being to enable a railway-carriage to be run upon either of two or more railway-tracks of different gages, as well as from, to, or upon the other, as circumstances may require.

In the drawings, *c* denotes a wheel-axle as provided with a sliding box, *e*, which slides endwise within a housing, *f*, which, when in use, is bolted or fastened to the frame of a railway-carriage, stands vertically, and is open at bottom except in being provided with a removable stopper, *a*, which not only serves to close the open part or mouth of the housing, so as to prevent the entrance of dust or extraneous matters into the housing, but operates to support the chock when at its lowest position and keeps it in connection with the housing.

The stopper *a* is formed as shown in top view in Fig. 7, and when in place it embraces the two portions *h h* of the chock, and is supported on two bolts, *i i*, which go horizontally through the housing, as shown in the drawings.

The chock *H*, formed as represented in the drawings, slides vertically within the housing, and is for the purpose of stopping the sliding box of the wheel-axle from longitudinal motion in a direction into or toward the hous-

ing whenever the said chock may be at its lowest position. While the chock may be at its highest elevation its recess or opening *k* will allow the box to slide into or through the chock and up to an opening, *l*, made through the front of the housing and provided with a closing-plate, *m*. It is through the opening *l* that access may be had to the interior of the sliding axle-box, either for the purpose of supplying its oil-chamber with lubricating material or for effecting the insertion or the removal of the journal with respect to the box.

The sliding box is hollow or furnished with a chamber, *n*, into which the journal *o* of the axle projects, and is held therein not only by a partition, *p*, extending across the chamber and partially around the journal, but by a flange or head, *q*, formed on the journal. There is also within the chamber *n* a movable composition bearing, *r*, which is supported against a wedge, *s*, which on being withdrawn from the box enables the bearing to be lifted within and removed from the box. The housing is also made with a packing-groove, *t*, to contain packing *u* to encompass the external surface of the sliding box, such groove and packing being to prevent the access of dirt or dust into the housing, as well as to cause the box during its movements to operate with little or no friction against the inner surfaces of the housing. Furthermore, there extends down from the housing a projection or lip, *s'*, which I term the "centralizer," its purpose being to maintain the truck frame or carriage at its proper position with respect to the rails while the wheels of opposite sides of the truck may be in the act of being moved either toward or apart from one another.

In my said patent I preferred to confine my invention to one subject, as indicated by the claim thereof, intending to explain and claim in a separate application for a patent what might be auxiliary to my main invention. I would remark, however, that I am aware that, although the sliding box, its housing, and axle, as combined and arranged in manner as herein described are new or of my invention, and also the combination of the same and the chock to be used in manner and for the purpose described is new with me and of my invention, I am also aware that it is not new to make the stationary box of a railway-carriage axle hollow or with an oil-chamber and a mov-

able bearing, as this is the plan of construction of the well-known "Lightner" box, and therefore I do not claim, in the abstract, the hollow box as made with the oil-chamber and the movable journal-bearing; but

I claim—

1. The combination of the sliding box *e*, made either with or without the oil-chamber, and either a stationary or a movable bearing, the housing *f*, and the axle *c*.

2. The combination of such parts and the chock *H*, arranged and applied to them so as to operate with them, substantially as specified.

3. The combination of the movable stopper *a* with the housing *f* and its chock *H*, the said stopper being for the purposes or to operate as specified.

4. The housing as made or provided with the packing-groove *t* and packing *u*, to encompass the sliding box, in manner and for the purposes specified.

5. The combination of the centralizer or lip *s* with the housing or truck frame or carriage thereof, when the latter has its wheels so applied as to be capable of being adjusted by means of a wheel-changing track to either of two tracks of different gages.

NAHUM F. BRYANT.
